UNITED STATES PATENT OFFICE.

EARLE S. MACPHERSON, OF DETROIT, MICHIGAN, ASSIGNOR TO HUPP MOTOR CAR CORPORATION, OF DETROIT, MICHIGAN, A CORPORATION OF VIRGINIA.

IGNITION-CABLE HOUSING.

Application filed July 21, 1924. Serial No. 727,355.

The invention relates to ignition cable housings which are designed particularly for use with internal combustion engines and has for one of its objects the provision of an improved housing for the ignition cables which has provision for the circulation of air. Another object is to provide a housing which may be readily secured to the cylinder head of an engine and which may be manufactured at relatively low cost. Further objects of the invention reside in the novel features of construction and combinations and arrangements of parts as more fully herein-after set forth.

15 In the drawings:

Figure 1 is a plan view, partly broken away, of a cylinder head having applied thereto an ignition cable housing embodying my invention;

20 Figure 2 is a side elevation partly in section thereof;

Figure 3 is a cross section on the line 3—3 of Figure 1.

1 is the cylinder head of an internal combustion engine and 2 are the spark plugs. 3 is the housing for the ignition cables which extends longitudinally above the cylinder head and is secured thereto.

25 The housing 3 is formed preferably of sheet steel, which is drawn to form a channel closed at its ends. The cylinder head 1 has the upwardly extending longitudinal projection or rib 4 in which the studs 5 are secured at longitudinally spaced points thereof. These studs extend upwardly through the top 6 of the housing and their upper ends are threadedly engaged by the nuts 7 for clamping the housing to the cylinder head with the open side of the former adjacent to the latter.

30 The main portions 8 of the housing side walls are spaced apart a distance less than the width of the longitudinal projection or rib 4 but the terminal portions 9 of these side walls and also of the housing end walls are spaced apart a distance greater than the width of the longitudinal projection or rib, these portions being connected by the lateral portions 10 which extend outwardly from the main portions. 11 are spacers preferably formed of sheet steel and secured to the lower sides of the lateral portions 10 by a suitable method such as spot welding. The lower side of each spacer is secured to a plate 12 which is adapted to engage the upper surface of the

longitudinal projection or rib 4. There is a spacer with its plate for each stud 5, the latter extending through the former. As a consequence the parts of the lateral portions 10 of the housing between the spacers are spaced above the upper surface of the longitudinal projection or rib of the cylinder head so that air may pass between the terminal and lateral portions and this projection or rib upwardly into the housing 3. Each plate 12 is preferably provided in its upper face with the longitudinal grooves 13 affording air spaces and decreasing the area of contact between the plate and the spacer secured thereto.

40 To position the ignition cables within the housing 3 the spacer 11 is preferably provided with the integral upwardly extending portions 14 substantially parallel with the side walls of the housing and spaced sufficiently from each other for the passage of the studs 11 therebetween. These guide portions serve to prevent the ignition cables from coming in contact with the studs while at the same time they permit the terminal portions 15 of the ignition cables to be led outwardly through openings in one of the side walls of the housing to the spark plugs.

45 With this arrangement the ignition cable housing is secured to the cylinder head in a manner to provide for passage of the air upwardly into the housing to assist in cooling the cables. Also the ignition cable housing is secured to the cylinder head in such a way that it may be readily attached to or removed therefrom. Furthermore the ignition cable housing has means for guiding or positioning the ignition cables and maintaining the same from contact with the studs which secure the housing to the cylinder head.

50 What I claim as my invention is:

1. The combination with the cylinder head of an internal combustion engine, of an inverted channel shaped ignition cable housing supported upon said head and having provision for the passage of air between said housing in sufficient amount to cool the ignition cables and head and upwardly into said housing.

55 2. The combination with the cylinder head of an internal combustion engine and ignition cables associated therewith, of an inverted channel shaped ignition cable housing and means for securing said housing to said head with the edges of said housing in

sufficient amount to cool the ignition cables spaced from said head to provide for the passage of air into the housing.

3. The combination with the cylinder head of an internal combustion engine having a projection extending therefrom, of a channel shaped ignition cable housing having the portions of its side walls adjacent said projections spaced therefrom, and means for securing said housing to said projection.

4. The combination with the cylinder head of an internal combustion engine having a projection extending therefrom, of a channel shaped ignition cable housing having side walls provided with outwardly extending lateral portions and substantially parallel terminal portions, means secured to said lateral portions for spacing the same from said projection and means secured to said projection and extending through said housing for securing said housing to said head and positioning said terminal portions at points spaced from said projection.

5. The combination with a channel shaped ignition cable housing, of means for positioning the ignition cables within said housing including a member having a guide portion extending between and substantially parallel to the side walls thereof.

6. The combination with the cylinder head of an internal combustion engine provided with a longitudinally extending upward projection, of an inverted channel shaped ignition cable housing having side walls provided with outwardly extending lateral portions and downwardly extending terminal portions, means for securing said housing to said head including a member secured to said projection and extending through said housing between its side walls and a member having a portion for spacing the lateral portions of the side walls from said projection and also having integral spaced upwardly

extending portions between which said securing member extends.

7. The combination with a cylinder head of an internal combustion engine, of an open bottom ignition cable housing supported upon said head, the longitudinally extending lower edges of the housing having provision for the passage of air between the cylinder head and the housing and into said housing.

8. The combination with a cylinder head of an internal combustion engine, of an open bottom ignition cable housing supported upon said head, the longitudinally extending lower edges of the housing having provision for the passage of air between the cylinder head and the housing and into said housing, and means spaced longitudinally of the housing for supporting the housing in spaced relation with said cylinder head.

9. The combination with a cylinder head, of an ignition cable housing supported above said head, ignition cables extending longitudinally within said housing, and means along the length of the housing for admitting air to the housing in sufficient quantity for cooling the cables.

10. The combination with a cylinder head, of an ignition cable housing supported above said head, ignition cables extending longitudinally within said housing, and means along the length of the housing for admitting air to the housing for circulation about the cables at a plurality of points along their length.

11. The combination with a cylinder head, of an ignition cable housing supported above said head, ignition cables extending longitudinally within said housing, and means permitting circulation of cooling air transversely of the cables at a plurality of points along their length.

In testimony whereof I affix my signature,
EARL S. MACPHERSON.
